UNITED STATES PATENT OFFICE

EARL M. BARDEN, OF DETROIT, MICHIGAN, ASSIGNOR TO PACKARD MOTOR CAR COMPANY, OF DETROIT, MICHIGAN, A CORPORATION OF MICHIGAN

STENCIL

Application filed February 18, 1930. Serial No. 429,384.

This invention relates to painting shields, masks or stencils and particularly to such devices for use on or near mouldings, beads or raised portions of surfaces which are to be 5 ornamented with paint or similar coloring matter.

It is a general object of the present invention to provide a novel and improved painting shield.

More particularly it is an object of the invention to provide a painting shield or mask in which provision is made to cause intimate contact between the edges of the opening cuts through the shield and the surface to be 15 painted so that no paint will run or be sprayed under these edges to fog or disfigure the pattern applied to the painted surface.

Another object of the invention consists in the provision of means for accurately positioning and holding the shield in position whereby the pattern applied through the shield is definitely located in respect to the boundaries of the surface on which it is to be applied.

An important feature of the invention consists in the arrangement of a painting shield in dished formation with a re-entrant bottom portion curved substantially on the surface of a cylinder and having a pattern 20 perforated therein whereby flexing of the whole shield will tend to increase the radius of curvature of the bottom portion to apply pressure to the edges of the pattern openings and insure a tight fit of the shield against the 25 raised surface on which a design is to be applied.

Another feature of the invention consists in providing a painting shield or mask with locating means adapted, for instance, to engage the edges of a moulding or bead and locate the shield so that the pattern therein will 30 be accurately positioned on the moulding.

Other and further features and objects of the invention will be more apparent to those skilled in the art upon the consideration of the accompanying drawings and following specification, wherein is disclosed a single exemplary embodiment of the invention with the understanding, however, that such changes 45 may be made therein as fall within the scope

of the appended claims without departing from the spirit of the invention.

In said drawings;

Figure 1 is a face view of a device constructed according to the present invention; 55

Figure 2 is a section on line 2—2 of Figure 1; and

Figure 3 is a section on line 3—3 of Figure 1 showing the device applied to a moulding on the body of an automotive vehicle. 60

The art of decorating with stripes and small designs on painted surfaces has developed slowly in spite of the great demand, particularly in the building of automotive vehicles, for a suitable mass production method. 65 Those men who are expert stripers command the highest pay of all skilled labor in connection with the building of vehicle bodies and their work requires so much time that the movement of the body through the assembly line is seriously delayed, yet the demand for striping is such that it must be applied, particularly, on the higher class vehicles. Since the advent of pyroxylin finishes the difficulty has been augmented, for these finishes dry so 70 rapidly that it is only with extreme difficulty that they can be handled with the striping brush. If the stripe is applied with ordinary paint then the final polishing operation on the pyroxylin wears it off. There has already been developed a suitable striping machine which is satisfactory for applying straight, parallel-sided stripes, but it has been 75 found that such a machine is not satisfactory for finishing the ends of the stripes or for applying curves or other ornamentation, and it is a purpose of this invention to provide a mask or shield which permits the application of pyroxylin paint by spraying. 80

This device functions in the nature of a 85 stencil but has certain novel features which enhance its usefulness, particularly where the operation is carried out on the surface of a moulding, bead or other raised portion of the vehicle body. The present embodiment of 90 the invention is particularly illustrated for use on beads on vehicle bodies, such as those occurring at the so-called belt line, just below the windows, but with slight variations, 95 it is susceptible to numerous other uses and 100

it is the intent of the claims of this application to cover these various modifications.

Referring particularly to Figures 1 and 3, there is shown at 10 the side of a vehicle body having either formed integral therewith or applied thereon the moulding or bead 11 which has a convex surface and rather a sharp angle 12 of junction with the body. As seen particularly in chain lines in Fig. 1 this moulding tapers to a point 13 where its end merges into the body. The present device is shown as provided with a cut-out pattern 14 through which paint is to be applied to the surface of the moulding which has already received its main coat of finish. The pattern here shown is intended to form the finish, at the end of the moulding, for two parallel stripes and so the cut-out includes portions 15 forming the beginning of such stripes.

20 The mask or stencil is formed from thin, springy sheet metal such as shim stock, as, for instance, steel about .008 inch thick. A sheet 16 of this metal is cut to the proper size, preferably rectangular, and the corners 25 have triangles removed therefrom so that the peripheral portions of the rectangular sheet may be bent upward until the side of the cut-outs meet as at 17 where they are secured together by soldering or welding to form the 30 mask into a dish-shaped device as clearly seen in Figure 2. This dishing has two functions. First, it materially strengthens the shield and gives it added rigidity, and second, it provides a lower edge which is substantially removed from the surface of the body so that 35 and dripping paint will not fall on this finished surface. Here it should be remarked that the stencil is customarily used on a substantially vertical surface as shown in Fig. 3.

40 The surface of the bead 11 on which the pattern is to be applied is substantially cylindrical and in order that the stencil may be accommodated to this surface, its bottom, in the area indicated by the reference character 18, is formed with a re-entrant portion best seen in Figs. 2 and 3, which has the contour of a sector of a cylinder of a radius substantially the same as that of the outer surface of the bead. This re-entrant portion 45 is somewhat wider than the full width of the bead and extends between the parts indicated by the reference characters 19 in Fig. 3 and longitudinally for the full length of the shield except where the turned-up ends leave 50 55 this surface.

It is necessary to accurately locate and position the shield on the bead and for this purpose it is provided with a plurality of positioning buttons 20 on its under or body-
60 engaging surface. Four of these buttons are shown, two to engage the upper edge of the bead and two the lower edge, so that the pairs of buttons are accurately spaced apart just the width of the bead. In effect they
65 are large headed rivets with the heads like

that of fillister screws. The stems of the rivets pass through holes in the shield and the inner ends are peened over, as at 21, to retain them in position. To locate the shield in respect to the end of the bead a large locating button 22 is provided, secured in position in the same manner as the buttons 20 and having in its side the notch 23 which receives the end of the bead and limits the movement of the shield longitudinally of the head. 70 75

In use the operator grasps the upper and lower edges of the shield between the thumb and fingers of one hand and presses the turned-up edges 24 slightly together as seen in the dotted line position of Fig. 3. This flexes the shield throughout the length of the re-entrant bottom portion. He then presses the shield into position, guided by means of the locating and positioning buttons, and attraction beneath the mask so that the pattern of the shield applies the coloring material, preferably with a conventional form of spray gun. As soon as this application is complete the shield is quickly withdrawn. The flexing of the re-entrant portion of the bottom causes all of the edges of the cut-out pattern 14, 15 to be tightly pressed into engagement with the surface of the bead so that intimate contact between these thin edges and the surface of the bead is obtained and there is no chance of the paint either being blown or running under the shield to fog or disfigure the final design.

The whole operation of applying the 100 shield, spraying the paint and removing the shield occupies but a few seconds as compared with about ten minutes for applying a similar design by a hand operation. As has already been pointed out, the intimate contact between the shield and the bead prevents 105 paint being sprayed or drawn by capillary attractive beneath the mask so that the pattern is clean-cut and accurate. The striping can be completed then by starting with the 110 sections of the stripe formed by the cut-out portions 15 and completed in the usual manner. The whole device is extremely simple both in its construction and operation and its time-saving features result in a material 115 saving in the cost of striping a vehicle.

Having thus described the invention, what is claimed as new and desired to be secured by Letters Patent is:

1. A stencil for use on raised surfaces comprising a resilient sheet having a design perforated therein and means on said sheet to engage the edges of said surface to position the sheet. 120

2. A stencil for use on mouldings, comprising a resilient sheet having a design perforated therein and means on said sheet to engage portions of the moulding to positively position the sheet in respect to the moulding. 125 130

3. A stencil for use on mouldings, comprising a resilient sheet having a design perforated therein, means on said sheet to engage portions of the moulding to position the sheet in respect to the moulding and means to cause close engagement of the design defining edges of the sheet with the surface of the moulding. 70
4. A stencil for use on mouldings, comprising a dished resilient sheet having a design perforated in a curved portion thereof. 75
5. A stencil for use on mouldings, comprising a dished resilient sheet, a reentrant portion at the bottom of the dish, said sheet having a design perforated in the reentrant portion thereof. 80
6. A stencil for use on mouldings, comprising a dished resilient sheet having a design perforated therein and means on said sheet to position said sheet in respect to the moulding. 85
7. A stencil for use on mouldings, comprising a dished resilient sheet, a reentrant portion at the bottom of the dish, said sheet having a design perforated in the reentrant portion thereof and means associated with said sheet to locate the sheet with respect to the moulding. 90
8. A paint shield for motor vehicle bodies comprising a resilient structure having thin edges adapted to be closely pressed against the part being painted by means external to the structure of the shield and sharply defining the limits of the shielded zone. 95
9. A paint shield for use in painting on or near mouldings on motor vehicle bodies, the paint limiting edges of said shield being thin and resilient to form a close fit with the surface to be painted when pressed thereagainst and positioning means on the work engaging face of the shield for locating it with respect to the moulding. 100
10. A paint shield for motor vehicle bodies comprising a pan-like member of resilient sheet metal having the bottom inwardly curved to substantially the contour of a cylindrical segment, a portion of said bottom being cut out to form a design and locating and positioning means on said bottom. 105
11. A paint shield for raised mouldings of automobile bodies comprising a sheet of resilient metal having a cutout to permit the passage of paint, the sheet being curved surrounding the cutout portion on a radius greater than that of the moulding. 110
12. A paint shield for raised mouldings of automobile bodies comprising a sheet of resilient metal having a cutout to permit the passage of paint, the sheet being curved surrounding the cutout portion on a radius greater than that of the moulding and means on the body engaging side of the sheet to engage the edges of the moulding to position the shield. 115
13. A paint shield for raised mouldings of 120
- automobile bodies comprising a sheet of resilient metal having a cutout to permit the passage of paint, the sheet being curved surrounding the cutout portion on a radius greater than that of the moulding, means on the body engaging side of the sheet to engage the edges of the moulding to position the shield and means to engage the end of the moulding to locate the shield in respect thereto. 125
14. A stencil for use on raised surfaces comprising a sheet having a design perforated therein and means on said sheet to engage the edges of said surface to position the sheet thereon. 130
15. A stencil for use on mouldings, comprising a sheet of material having a design perforated therein and means associated with said sheet to engage portions of the moulding to position the sheet in respect thereto. 135

In testimony whereof I hereunto affix my signature.

EARL M. BARDEN.
